UNITED STATES PATENT OFFICE

ROBERT CLAYTON, OF OVERBROOK, PENNSYLVANIA, ASSIGNOR OF ONE-FOURTH TO
P. FRANK SONNEK, OF WOODHAVEN, NEW YORK

REFRIGERATION APPARATUS

Application filed December 6, 1930. Serial No. 500,505.

This invention relates generally to refrigeration, and is more particularly directed to improvements in refrigerating machines of those types intended for household and similar uses, wherein so-called drawers or trays are utilized as receptacles in which water is frozen to produce cubes or other shaped blocks or pieces of ice.

As is well known, in existing types of refrigerating machines, the drawers, or trays for freezing desserts, or water for producing ice, are contained within the cooling unit. During the freezing process moisture from the atmosphere and from the foods placed in the refrigerator collects on the cooling unit and the associated drawers or trays, forming an ice-coating, or frosting between the walls of the drawers or trays and the compartments within which they are housed, so that they are virtually sealed in position within the cooling unit. Therefore, when it is desired to withdraw or remove a tray from the cooling unit, it is necessary to break the ice or frost seal which, due to the relatively small clearances between the trays and the surrounding walls of the cooling unit, is extremely difficult to accomplish without damage to the trays or to the walls of the cooling unit. A knife, screw-driver, ice-pick, or other relatively flat sharp implement is customarily employed to effect a cleavage of the line of icing or frosting which binds the trays to the cooling unit walls, and, in many instances, the trays or walls are badly bent, and sometimes cut or perforated in the operation of breaking the ice seal, so that the trays may be withdrawn to make their contents accessible.

Various attempts have been made to prevent the formation of the ice seal about the trays by the use of non-freezing solutions interposed between the base and sides of the trays and the walls of the cooling unit, and by mechanical means which are designed to effect a tilting movement of a tray prior to the manual withdrawal movement thereof. However, none of these expedients has proven successful in practical use of refrigeration apparatus, which, obviously is placed in the hands of those who are unskilled in the proper handling of such devices. In some cases,

manufacturers of refrigeration machines of the household types have endeavored to solve the problem by increasing the clearance between the sides and bottoms of the trays and the walls of the cooling unit. However, this has been found to be ineffective, and, furthermore, materially prolongs the period which is required for freezing the contents of the trays. Again, the loosely fitting trays do not give the cooling unit the desired finished appearance.

Therefore, it is the primary object of this invention to provide a mechanical means for breaking the ice seal between the sides and bottom of an ice tray, or drawer, and the walls of the compartment of a cooling unit of the refrigerating machine within which it is housed, which is of a simple and durable construction, and which will overcome the disadvantages that are inherent to previous forms of the mechanical devices of the kind and to the use of non-freezing solutions.

More specifically, it is the object of this invention to provide a mechanism which may be readily manipulated by one desiring to withdraw an ice tray from the cooling unit within which it is housed, to break the seal produced by the surrounding ice, ice film, or coating, by effecting the bodily movement of the tray in a vertical plane, the means which I utilize being susceptible of incorporation in existing refrigerating machines, as well as in apparatus especially designed for its use.

A further object of my invention is to provide mechanical means, manually actuatable, to simultaneously effect the movement of an ice tray, relative to a compartment in which it is enclosed, in two intersecting planes, so that by a single movement the ice seal will be broken and the tray partially expelled or extruded from its compartment.

Other objects and advantages flowing from the practicing of my invention will doubtless become evident as the description proceeds, and I would have it understood that I reserve unto myself all rights to the full range of equivalents, both in structure and in uses, to which I may be entitled under my invention in its broadest aspect.

For the purposes of this disclosure, I have

elected to show and describe a certain embodiment of my invention. However, my invention may take other forms and various changes in the structure of details may be made without departing from the spirit and scope of my invention, as defined by the appended claims.

In the drawings:

Fig. 1 is a front elevation of a cooling unit 10 of a conventional design with cooperating freezing trays, in which my invention is incorporated.

Fig. 2 is a vertical cross section of the structure shown in Fig. 1, disclosing the position 15 of the releasing mechanism or means when the tray is enclosed within the cooling unit for the freezing of the material therein contained.

Fig. 3 is a view similar to Fig. 2, illustrating 20 the mode of operation of the tray-releasing means, and

Fig. 4 is a view in perspective of the tray-releasing mechanism.

Referring now to the drawings in detail, in 25 which like characters of reference are employed to designate similar parts in the several views, 7 indicates the cooling unit, and 8 the dessert or water-freezing tray, which is of the conventional oblong or rectangular 30 shape having a front face 9 formed with a portion 9^a which projects above the upper edges of the meeting side portions or walls of the tray. The vertical dimensions of the compartment within which the tray is housed 35 is slightly greater at its front end than the depth of the body portion of the tray, so that when the tray is in position for the freezing of the material therein, the aforesaid upwardly projecting portion 9^a of the front face 40 of the tray will abut upon the front wall of the compartment 7, so as to present a finished and pleasing appearance to the observer of the unit.

Below each tray which may be supported 45 within the cooling unit by any suitable means, as, for example, the ways or tracks 7^a I provide a shaft or rod 10 which is mounted in bearings 11 and 12 located in 50 the front and rear walls, respectively, of the cooling unit compartment 7, these bearings being preferably of an anti-friction material.

Mounted on the aforesaid shaft 10, and keyed or otherwise fixed thereto to rotate 55 therewith, are a pair of cams 13 and 14, one being positioned between the vertical center line of the tray and the front wall of the compartment, while the other is intermediate of said center line and the rear end of the tray.

Also mounted on said shaft 10 adjacent its inner end is a cam 15 having a surface 15^a, which normally abuts upon the rear wall of the tray 8 and functions as a stop in conjunction 60 with the portion 9^a of the front wall 9 of the tray to locate the latter when it is

wholly enclosed within the cooling unit compartment of the refrigerating machine.

As will be observed, the forward end of the shaft 10 projects through the bearing 11 and is provided with a handle or grip 16, whereby the shaft may be manually rotated to bring the effective surfaces of the cams 13 and 14 into contact with the bottom of the tray so as to exert an upward pressure thereupon, it being apparent that the rotative movement of the shaft to function the cams 13 and 14 will also actuate the cam 15 in engagement with the rear wall of the tray to effect the movement of a tray in a direction parallel to the longitudinal axis of said shaft. 75 In other words, a single rotative movement of the shaft 10 will simultaneously produce a bodily movement of the tray 8 in a vertical and in a horizontal plane, the forces generated by the action of the cams 13 and 14 and the cam 15 being ample to break any ice or frost which may have formed between the bottom and walls of the tray and its supports or the surfaces of the surrounding compartment, it being obvious that the effective 80 surface of the cam 15 is designed to produce a continuing expelling movement of the tray which will insure the contents of the tray against spillage of any liquid material which may have been placed in the tray for a brief 85 period of cooling or chilling.

When the tray has been expelled to the position shown in Fig. 3, it may be readily withdrawn from the compartment by means of the usual handle 9^b provided on its front 90 face 9.

From the foregoing description of my invention, it will be manifest that I have devised a simple, economical, and effective means for attaining the objectives to which this invention is directed. Further, by a single movement the ice seal is broken and the tray simultaneously expelled from the compartment in a position where it may be readily withdrawn without canting it transversely or longitudinally with the oftentimes objectionable consequences of existing devices of the prior art.

I claim:

1. The combination with a cooling unit of a refrigerating machine adapted to house a tray in which water may be frozen, of means for breaking ice which may form between said tray and the surrounding portions of said cooling unit, said means embodying elements for simultaneously applying pressure to said tray in intersecting planes.

2. The combination with a cooling unit of a refrigerating machine adapted to house a tray in which water may be frozen, of means for breaking ice which may form between said tray and the surrounding portions of said cooling unit, said means including a shaft, cams carried by said shaft formed to engage the base of said tray and means con- 130

trolled by the rotative movement of said shaft for applying pressure to the rear wall of said tray.

3. The combination with a cooling unit of a refrigerating machine adapted to house a tray in which water may be frozen, of means for breaking ice which may form between said tray and the surrounding portions of said cooling unit, said means including a 10 shaft mounted beneath said tray, a plurality of cams fixed to said shaft, certain of said cams having surfaces for engagement with the base of said tray, another of said cams contacting with the rear wall of said tray and 15 means for rotating said shaft to simultaneously render all of said cams effective to move said tray vertically and horizontally, the horizontal movement being in a direction outward from said compartment.

20 4. The combination with a cooling unit of a refrigerating machine adapted to house a tray in which water may be frozen, of means for breaking ice which may form between said tray and the surrounding portions of 25 said cooling unit, said means including a shaft mounted in bearings in said compartment below said tray, a plurality of cams fixed to said shaft, certain of said cams being normally out of contact with said tray 30 and having surfaces engageable therewith to exert an upward pressure on the bottom thereof, another of said cams being in contact with the rear wall of said tray and having a surface effective thereupon to exert 35 pressure upon said wall to move said tray longitudinally and means for rotating said shaft to simultaneously function all of said cams to effect the bodily movement of said tray in two intersecting planes.

40 5. As a new article of manufacture, a device adapted for incorporation in a refrigerating machine for releasing removable ice-bound trays from the cooling unit thereof, said device comprising a shaft having cams 45 fixed thereto, said cams being respectively located between the transverse axis of said shaft and its ends, said cams being adapted to engage the bottom of a tray when said shaft is mounted therebelow, and an additional cam on said shaft shaped to engage the rear wall of a tray, all of said cams being designed to simultaneously cooperate upon the rotation of the shaft to apply pressure to a tray with which they are engaged 50 to move the same vertically and horizontally.

55 6. A means for releasing an ice-bound tray from the cooling unit of a refrigerating machine by applying pressure to said tray to effect the bodily movement thereof in two intersecting planes, including a plurality of elements adapted to engage said tray and a common actuating means for all of said elements operable by a single movement to effect the release of said tray as aforesaid.

85 ROBERT CLAYTON.
